UNITED STATES PATENT OFFICE.

FREDERICK W. JENSEN AND CARL J. L. OLSEN, OF NEW YORK, N. Y.

HOSPITAL-BED.

SPECIFICATION forming part of Letters Patent No. 244,612, dated July 19, 1881.

Application filed September 29, 1880. (Model.)

To all whom it may concern:

Be it known that we, FREDERICK W. JENSEN and CARL J. L. OLSEN, of the city, county, and State of New York, have invented a new 5 and useful Improvement in Hospital-Beds, of which the following is a specification.

The object of our invention is to construct a bed especially adapted for hospital use, and convenient for giving all the necessary attention to the sick.

Our improvements relate to the construction of the bedstead, and to devices combined therewith for the use of the sick person. We use an iron-frame bedstead, the bottom of which is 15 formed by longitudinal rods sustained by cross-bars and held in place by nuts at their ends. The head and foot boards are hung in slots in the side rails, so that they can be adjusted or 20 swung down out of the way to give free access to the person on the bed. Combined with the bed we use a swinging arm carrying a vessel, which frame is fitted for being raised to carry the vessel through an aperture provided in the bed-bottom and mattress. The bed is also fitted with devices for automatically removing 25 and replacing the cover of the vessel as it is moved to and from its place. All of these features are described hereinafter with reference to the accompanying drawings, forming part 30 of this specification.

In the drawings, Figure 1 is a side elevation, partly in section, of our improved bed. Fig. 2 is a plan view of the same, and Fig. 3 is a vertical transverse section on line xx of Fig. 2.

Similar letters of reference indicate corresponding parts.

The frame of the bed consists of side bars, a , end bars, b , and intermediate cross-bars, c , which are metal, and the frame is supported on legs d . The bottom consists of small rods e , which extend over cross-bars c and through the end bars, b . The ends of rods e are fitted with nuts e' , by which the rods can be tightened and are held in place.

The head-board f and foot-board g are made as metal frames attached on rods h , that are fitted across the bed in slots i of the side bars, a . The boards f g are held upright by legs or projections f' , that engage with notches g' formed 50 in the upper edges of side bars, a , and there are two notches, g' , in each side bar, at the

head, so that the board f can be moved inward over the mattress to support the patient in a sitting position. The slots i are made long, so that the boards f g can be turned down, as 55 shown in dotted lines in Fig. 1, whereby they will be out of the way and surgical operations can be more readily performed.

From the bar a , at one side of the bed, rods k k' depend, which rods are fitted with loose 60 sleeves l , that carry arms m m' , and the sleeves are also provided with handles l' for their operation, as hereinafter described. The arm m , hung on rod k , has its outer end formed with an upward projection to enter a socket of the vessel 65 n , whereby the vessel is held in an upright position on arm m and can be removed therefrom at will. The vessel n is provided with a sliding cover, n' . The arm m' , hung on rod k' , carries at its outer end a plug, o , consisting of 70 a tube, upon the upper end of which is fixed a pad of soft material.

At the center of the bed-bottom is fitted a tube, p , large enough to receive the vessel n , and the mattress q is formed with an aperture 75 over the tube p and corresponding in size therewith. By this construction either the vessel n or plug o can be turned beneath the opening in the bed and then raised to extend through tube p and the aperture of the mattress. The 80 plug is intended to remain in the opening at all times when the vessel is not required for use, to prevent irritation of the patient by the edges of the opening; but this plug may be dispensed with if not required. To hold the 85 arms m m' up, and sustain the vessel and plug, a sliding spring-pin, r , is fitted at the side of the bed for engagement with notched lugs p' on arms m m' , as shown in Fig. 3. The cover n' of the vessel is provided on its upper side 90 with a notched plate that forms undercut lugs n^2 , and at the under side of the bed is an arm, s , having at its outer end a disk, t , (see detail Fig. 4,) forming flanges that are held in position for passing beneath the lugs n^2 of the cover 95 as the vessel is swung beneath tube p , so that the cover is caught and held, thereby removing the cover from the vessel. There is also hung beneath the bed, on a stud, u' , a double arm, u , moved in one direction by a spiral 100 spring on the stud, which arm is held in the path of the vessel n , so as to be moved thereby.

The arm is formed with its shorter portion curved to the shape of cover n' . The arm u is moved forward by the vessel as the latter swings in, and its curved portion takes against 5 the back of the cover when the vessel reaches its place. The arm u thus serves to retain the cover on the arm s , and also, by its spring, start the arm m back when the vessel is drawn back. The cover slides to place on the vessel 10 as the arm m returns, and the spring-arm u insures sufficient movement of the arm to replace the cover, so that the vessel may not be left uncovered.

The sleeves l l' and arms m m' are to be operated by the handles l^2 . The vessel may remain on the arm beneath the bed ready for use. To prevent the arm from swinging out accidentally the sleeve l is notched, as shown at v , for engagement with a brace, w , that connects the lower ends of rods k k . By raising sleeve l the notch is cleared, so that the arm can be swung out for removal of the vessel.

The bed constructed as described is amply ventilated, and is convenient for use to both 25 the patient and the attendants.

Having thus fully described our invention, we claim as new and desire to secure by Letters Patent—

1. The bed - frame for hospital - beds, consisting of side bars, a , end bars, b , and cross-

bars c , and having a bottom consisting of rods e , provided with tightening-nuts e' , substantially as shown and described.

2. In hospital-beds, the head and foot boards f g , provided with lugs f' , and attached on rods h , combined with the slotted side bars, a , having notches g' , substantially as and for the purposes set forth. 35

3. The combination, with a bed having a central opening, of arm m , carried by rod k , and removable vessel upon the arm m , substantially as and for the purposes set forth. 40

4. The combination, with an apertured bed and mattress, of the arm m' , carried by rod k' , and provided with plug o , substantially as and 45 for the purposes set forth.

5. In hospital - beds, the fixed arm s , provided with disk t , swinging arm m , vessel n , and cover n' , provided with lugs n^2 , combined for operating substantially as and for the purposes set forth. 50

6. The spring-arm u , hung on stud u' , combined with the swinging arm m , vessel n , cover n' , and devices for removing the cover, substantially as and for the purposes set forth.

FREDERICK W. JENSEN.

CARL J. L. OLSEN.
